MACHINE SUPPORT TRAY

James L. Rutzick, 1540 Goodrich Ave.,
St. Paul, Minn. 55105

Filed July 5, 1972, Ser. No. 269,110

Term of patent 14 years

Int. Cl. D15—99

U.S. Cl. D55—1 H

FIG. 1

FIG. 2

FIG. 3

FIG. 4

FIG. 1 is a top plan view;

FIG. 2 is a side elevational view taken from the right side of FIG. 1;

FIG. 3 is a bottom plan view; and

FIG. 4 is a sectional elevational view taken along line 4—4 of FIG. 1.

The elevational view from the remaining three sides is identical with that of FIG. 2 except for omission of the small centrally located outlet connection.

I claim:

The ornamental design for a machine support tray, substantially as shown and described.
